UNITED STATES PATENT OFFICE.

FREDERICK F. BILHOFER, OF NEW YORK, N. Y.

DESIGN FOR A STOOL.

SPECIFICATION forming part of Design No. 31,697, dated October 17, 1899.

Application filed September 20, 1899. Serial No. 731,127. Term of patent 7 years.

To all whom it may concern:

Be it known that I, FREDERICK F. BILHOFER, a citizen of the United States, residing at New York, in the county of New York and State of New York, have invented and produced a new and original Design for Stools, of which the following is a specification, reference being had to the accompanying drawings, forming a part thereof, of which—

10 Figure 1 is a side view of a stool, showing my new design; and Fig. 2 is an end view thereof.

As shown in the drawings, the leading or material feature of my design consists of a transverse cross-piece 1, having a semicylindrical or convex top 2 and a straight bar or rod 3, extended downwardly from the under side of said top cross-piece. The top and sides of the top cross-piece 1 are formed by 15 the curved semicylindrical or convex surface, while the bottom of said cross-piece is flat or straight, as shown at 4. The ends 5 5 of said top cross-piece 1 are straight and relatively

parallel, as shown in Fig. 1. The straight bar or rod 3 is shown cylindrical in contour, 25 and it extends downwardly from the top cross-piece 1 from a point at about the center of the flat under side 4 of the same. Said rod 3 is shown with a circumferential cylindrical enlargement or knob 6 at its lower end. It will 30 be understood that the rod or bar 3 extends at right angles to the transverse convex top cross-piece 1.

Having fully described my invention, what I claim as new, and desire to secure by Letters Patent, is—

The design for a stool, as herein shown and described.

In testimony that I claim the foregoing as my invention I have signed my name, in presence of the subscribing witnesses, this 18th day of September, 1899.

FREDERICK F. BILHOFER.

Witnesses:

F. A. STEWART,
K. E. LANGTRY.
